United States Patent Office.

HENRY F. HAACK, OF NEW YORK, N. Y.

Letters Patent No. 102,810, dated May 10, 1870.

IMPROVEMENT IN PADLOCKS.

The Schedule referred to in these Letters Patent and making part of the same.

To all whom it may concern:

Be it known that I, HENRY F. HAACK, of the city, county, and State of New York, have invented a new and improved Padlock; and I do hereby declare that the following is a full, clear, and exact description thereof, which will enable others skilled in the art to make and use the same, reference being had to the accompanying drawing forming part of this specification, in which—

Figure 1 represents a face view of my improved padlock, showing it locked.

Figure 2 is a face view of the same, showing it unlocked.

Figure 3 is a side view of the key.

Similar letters of reference indicate corresponding parts.

My invention relates to that class of padlocks whose tumblers are operated by pushing a flat key against them; and

The invention consists in the arrangement of the locking-dog so as to lock into the hasp from the front side, and having tumblers pivoted thereto at its lower extremity, in combination with a stationary stop, as hereinafter specified.

A, in the drawing, represents the case or shell of the lock.

B is the ball or link of the same.

C is the bolt, pivoted to the lock-case by a pin, a, and provided with a hook, b, which locks into the notched or perforated end of the bail, as in fig. 1.

D D are the tumblers.

They are, by a pin, c, pivoted to the surface of the bolt, and are slotted to work on a pin, d, that projects from the lock-case, as shown. The slots in the tumblers are nearly T-shaped.

The springs e hold the tumblers in the position shown in fig. 1, in which the pin d is in the upper end of their slots, thereby preventing the bolt to move.

When the key E is inserted through a slot in the

side of the lock-case, it strikes first against the tumblers and raises them so as to bring the arms f of their slots into line with the pin d.

The parts f of the slots are all on a circle described around the pin a. The key can now move when it reaches the bolt, swing the same on its pivot a, and draw its hook off the link B.

As soon as the link B is liberated from the bolt it is thrown open by a spring plate, F, pivoted in the lock-case.

This spring plate has also a projecting ear, g, which arrests the bolt as in fig. 2, keeping the same in such a position that the device will be self-locking.

The end of the link, when forced into the lock, will come between the ear g and the end of the hook b, pushing both aside and descending into the lock.

As soon as the aperture or recess of the link arrives in line with the hook b, the latter is, by the bolt-spring h, forced into such aperture or recess to lock the link.

The peculiar characteristic of this lock consists in the arrangement of the tumblers upon the bolt, and in the combination of those parts with the spring plate F.

I wish to be understood as making no claim broadly to the combination of a stationary stop, pivoted tumblers, and dog; but

Having thus described my invention,

I claim as new and desire to secure by Letters Patent—

A padlock having a locking-dog, C, pivoted centrally, and arranged to lock into the hasp from the front side, with the tumblers D pivoted thereto at its lower extremity, in combination with the stationary stop d, all as set forth and shown.

HENRY F. HAACK.
